UNITED STATES PATENT OFFICE.

ERNST HJALMAR CARLSSON, OF OSKARSHAMN, SWEDEN.

ROAD-STAMPING MACHINE.

Application filed May 10, 1927, Serial No. 190,158, and in Sweden January 21, 1927.

This invention refers to a road stamping machine with one or more double-acting stampers working perpendicularly to the road, and the said invention has for its object 5 to produce a road stamping machine of a simple and solid construction and with a very great capacity.

The accompanying drawings show as an example a suitable embodiment of the invention, and

Figure 1 is a side-view of the stamping machine,

Figure 2 is a plan-view of same,

Figure 3 is a front-view of the stamping machine on a larger scale and partly in section on lines 3—3 of Figure 2,

Figure 4 is a section on the lines 4—4 of Figure 2, drawn on a larger scale,

Figure 5 is a side-view on a greater scale 20 of two stampers engaging each other,

Figure 6 is a horizontal section on the lines 6—6 of Figure 5, and

Figure 7 is a section through some details on the lines 7—7 of Figure 4.

According to the shown embodiment the road stamping machine is provided with two equal stamping systems, each comprising one or more (in the drawing two) double-acting stampers 1, 2. The stamper 1 has working 30 surfaces 3 at both of its ends, and the stamper 2 is provided with two working surfaces 4 in the same manner. In the stamper 1 there is a longitudinal groove 5 and the stamper 2 has a similar groove 6. The two stampers are 35 adapted to clasp or engage one another with freedom of motion, as is especially to be seen from Figures 2, 5 and 6, so that one may work without being hindered by the other.

On a stationary main shaft 7 two discs 8 for 40 each stamping system are rotatably mounted and firmly connected to one another by a number of (in the drawing three) transverse pins 9 serving as carriers for the stampers. One of the discs is provided with a toothed 45 wheel 10 meshing with another toothed wheel 11 stationarily mounted on a rotatable shaft 12 which is driven in a suitable manner. When the shaft 12 is rotating the discs 8 are rotated in the direction of the arrow (Figures 1 and 4).

An eccentric 13 is rotatably mounted on the

stationary shaft 7 and cooperates with the stampers 1 and 2. The said eccentric which rotates in a direction opposite to the discs 8, see the arrow of Figures 1 and 4, is adapted 55 to raise the stamper for a small distance immediately after each downstroke. The eccentric 13 is firmly connected to a neck or hub 14, Figures 3 and 7, one end of which is provided with a toothed wheel 15 meshing with another toothed wheel 16 fixed on a rotatable shaft 17 (best to be seen in Figure 3) which is driven in a suitable manner.

On the stationary main shaft 7 between the discs 8 a cam 18 is fixed for each stamping system said cam serving as a guide for the stampers. The cam 18 has not only an arched sliding surface 19 extending for some distance along the periphery of the discs 8 but also a vertical sliding surface 20 having in 70 its middle a projecting ear 21 jammed on the main shaft 7. The said cam has at its top and at its bottom beveled portions 22 connecting the vertical sliding surface 20 with the arched sliding surface 19. As is to be seen from Figures 3 and 7 the cam is provided with a recess 75 23 opposite to the eccentric 13 so that the eccentric may rotate without being hindered by the cam.

The stamping systems are supported by 80 rollers or the like in such a manner that the rotating discs 8 do not touch the road. The number of rollers may be varied according to circumstances. In the shown embodiment there are two anterior rollers 24 stationarily 85 mounted on a shaft 25 parallel with the main shaft 7, the shaft 25 being rotatably mounted in the frame 26. Further, there are two posterior rollers 27 fixed on a shaft 28 journaled in the frame, Figures 1 and 2. To the posterior rollers 27 driving power is transmitted in a suitable manner from a motor located on the stamping machine for moving the stamping machine forward on the road in one or the other direction, the said motor driving also 90 the discs 8 and the eccentrics 13. According to the drawing the stamping machine is moved forward in the direction of the arrow 30, Figure 1. The rollers 24, 27 also serve to smooth the road to some extent after the 100 stamping. Evidently, wheels may be used instead of the rollers, if desired, but in this case

no subsequent smoothing of the road is effected by the machine.

Figure 4 shows one of the stampers 1 in rammed down position, while the other 5 stamper is being swung upwards in falling position by one of the pins 9 of the discs 8. The eccentric 13 which is rotated in opposite direction to the discs 8 raises the stamper for a small distance from the road immediately 10 after the downstroke. Figure 4 shows the eccentric just about raising the stamper 1. During the first portion of its upward movement, Figure 4, the stamper is guided by the eccentric 13 and is forced to follow the 15 arched sliding surface 19, and during the last portion of its upward movement, the stamper follows the arched sliding surface on account of its weight. As soon as the stamper 2 has reached the beveled surface 22 of the cam 18, 20 the stamper slides down on said beveled surface, is released from the pin 9 and falls down along the sliding surface 20. As soon as the stamper 2 has fallen down, it is immediately 25 raised by the eccentric 13, as has already been described in connection with the stamper 1. The other stamper 1 continues the while its swinging motion, and the stamper 2 raised by the eccentric 13 begins again to be swung upwards. When the stamper 1 has reached the 30 upper beveled surface 22 the downstroke is effected in the same manner as has just been described in connection with the other stamper.

As is to be seen from the aforesaid the 35 stampers work perpendicularly to the surface of the road. By choosing a large diameter of the discs 8 so that a great height of fall may be obtained and by rendering the stampers sufficiently heavy very vigorous strokes are 40 effected so that the road is stamped effectively.

The number of stampers 1 and 2 of each stamping system may be varied according to 45 circumstances. Thus, one may use a single stamper, in which case the discs 8, however, must rotate with a comparatively great speed, in order that a sufficient number of strokes per minute may be obtained. However, it is most advantageous to use two or more stampers in each stamping system, in which case one may let the discs 8 rotate comparatively slowly and, nevertheless, one may obtain a very great number of strokes per minute. Presume the discs 8 to make twenty revolutions per minute one obtains with two stampers sixty strokes per minute. Consequently, the road stamping machine will get a very great capacity, if one chooses sufficiently large working surfaces on the stampers.

55 In the embodiment shown and described two stamping systems are used but one may, of course, use one stamping system only, if desired, or also more than two stamping systems.

60 The shown and described embodiment may

evidently be varied in many respects without the idea underlying the invention being given up.

Having now described my invention, what I claim as new and desire to secure by Letters Patent is:

1. A road tamping machine, comprising a double end tamper, and means for rotating the tamper from one upright position to another to permit said tamper to fall of its own weight and bring alternate ends thereof into contact with the ground. 75

2. A road tamping machine, comprising a double end tamper, means for rotating the tamper from one upright position to another 80 to permit said tamper to fall of its own weight and bring alternate ends thereof into contact with the ground, and means operating subsequent to movement of the tamper into contact with the ground to lift the tamper off the 85 ground before continuing its rotary movement.

3. A road tamping machine, as claimed in claim 2, including means for supporting the tamper in its raised position during rotary 90 movement thereof from one fall to the next and for releasing the said tamper when the latter has reached its upright position.

4. A road tamping machine, as claimed in claim 2, in which the means for rotating the tamper comprises a continually revolving member having carriers movable with the member into engagement with the said tamper in its fallen position to carry the latter to its alternate upright position. 100

5. A road tamping machine, as claimed in claim 2, including a stationary cam in the path of the tamper to support it from one raised position to the next and for releasing the latter as it reaches its upright position. 105

6. A road tamping machine, as claimed in claim 2, including a stationary cam having a curved surface disposed in the path of the tamper to support it during movement thereof from one raised position to the next and an upright guide to guide the tamper in its fall to engage the ground. 110

7. A road tamping machine, as claimed in claim 2, including a fixed cam in the path of the tamper to hold it in its raised position during movement thereof from one upright position to the next, and in which the means for lifting the tamper comprises a rotary cam to first lift the tamper free of the ground and then against the first cam until the tamper has passed the horizontal plane in its upward rotary movement. 115

8. A road tamping machine, comprising a rolling carriage, a rotary axle operated from the carriage, a pair of spaced discs mounted on and turning with the axle and provided with connecting pieces disposed therebetween, a plurality of tampers disposed between the discs, each thereof being provided with a slotted mid portion for the axle and a 120

125

130

- tamping surface at opposite ends, which ends are engaged by the connecting pieces to impart movement of the tampers from one upright position to the next, a fixed curved cam 5 in the path of the tampers moving from their opposite upright positions to guide them and an upright guide surface to guide the tampers during their fall, and a rotary cam turning with the axle and engaging each tamper subsequent to its fall to lift and support it during 10 its travel to a horizontal plane.

In witness whereof, I have hereunto signed my name.

ERNST HJALMAR CARLSSON.
